UNITED STATES PATENT OFFICE

WILLIAM P. GIBERSON, OF BERKELEY, CALIFORNIA

CIGARETTE EXTINGUISHER

Application filed June 25, 1928. Serial No. 287,928.

This invention relates to improvements in devices for extinguishing cigarettes.

An object of my invention is to provide a manually operated device for conveniently extinguishing lighted cigarettes.

Another object of my invention is to provide a manually operated device for extinguishing cigarettes wherein is embodied convenient means for detachably securing the

10 same to a suitable support.

Other objects more or less apparent will present themselves or will be specifically pointed out in the description to follow.

15 In the accompanying drawings,

Fig. 1 is a perspective view of a cigarette extinguishing device embodying my invention, showing a cigarette in position therein for extinguishment;

Fig. 2 is a front view of the device, showing a part of the hand manipulated plate broken away; and

Fig. 3 is a side view of the same.

Referring to the drawings, the numeral 1 represents a body member constructed from 20 flexible sheet metal such as iron, having its top part bent outwardly as at 2 and downwardly as at 3. The device is attachable to a support in various ways, one of which is to position a support 4 between the body 1 and the downwardly disposed part 3 with the outwardly bent part 2 resting on the top edge of the said support.

The lower end of the body member 1 is bent outwardly and inwardly to form a semi-circular shaped spring part 5, the latter terminating in an upwardly extending inclined part or member 6. The points at which the upwardly extending inclined part 6 is joined to the semi-circular shaped spring 5 are positioned adjacent but separated from the lower end of the body member 1, and the top edge of the said part 6 is positioned in a widely separated location from the top end of the said body member. The upwardly extending inclined part 6 is moved toward the body member by grasping the said part by the hand and pressing it toward the body member. After the upwardly inclined part 6 is 50 released, the spring 5, which has been con-

tracted, causes the same to return to its normal position.

A lighted cigarette 7 may be extinguished by firstly placing the same between the body member and the upwardly extending inclined part 6 and then moving the said part 6 toward the said body member until the cigarette is firmly pressed between the said body and the part 6.

It is obvious to those skilled in the art 60 that my improved cigarette extinguisher may be constructed in other shapes and may be attachable to various kinds of supports in other ways than those shown on the drawings. So for these and other apparent reasons I desire my invention included broadly within the spirit of the appended claim.

Having described my invention, what I claim is:

A cigarette extinguisher comprising an 70 integral sheet of flexible material having an outwardly and upwardly extending part located at one end thereof, which said upwardly extending part may be actuated toward the sheet of material to compress a 75 cigarette, the said sheet of material also having a downwardly extending part for attachment and detachment to and from a support.
